J. S. BARNES,
INTERNAL-COMBUSTION ENGINE,
APPLICATION FILED MAY 28, 1917.

Patented Aug. 20, 1918.

Inventor
John S. Barnes
Attorney
J. S. Thomas

UNITED STATES PATENT OFFICE.

JOHN S. BARNES, OF DETROIT, MICHIGAN.

INTERNAL-COMBUSTION ENGINE.

1,276,004.

Specification of Letters Patent. Patented Aug. 20, 1918.

Application filed May 28, 1917. Serial No. 171,421.

To all whom it may concern:

Be it known that I, JOHN S. BARNES, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

My invention relates to internal combustion engines, as shown in the accompanying drawings and more particularly pointed out in the following specification and claims.

One of the objects of this invention is to secure the efficiency of a long stroke motor while only admitting to the combustion chamber a relatively small fuel charge.

Another object of this invention is to diminish the wear of the piston and cylinder through the reduction of the length of travel of the respective parts.

Other advantages and improvements will hereafter appear as the description proceeds, it being understood that changes may be made in the precise embodiment disclosed without departing from the spirit of the invention.

In the drawings—accompanying this specification—

Figure 1 is a vertical sectional view through an internal combustion engine showing the piston as it would appear at the end of the compression stroke and also at the end of the exhaust stroke.

Fig. 2 is a diagrammatic view showing the piston at the first portion of the suction stroke.

Fig. 3 is a diagrammatic view showing the piston at the end of the suction stroke.

Fig. 4 is a diagrammatic view showing the piston at the beginning of the compression stroke.

Fig. 5 is a diagrammatic view showing the piston at the end of the firing stroke.

Referring now to the letters of reference placed upon the drawings—

50 A, denotes an internal combustion engine, B, its cylinder, C, its crank-case. D, indicates a piston, comprising two concentric sleeves E, and F, which operate in conjunction but have an independent movement with respect to each other. G, designates a piston rod connecting the inner sleeve F,

with the crank shaft H, I, indicates packing rings carried by the sleeve E. J, denotes a divided peripheral ring carried by the sleeve F, which is adapted to expand as the piston travels in an outward direction entering a tapering recess e, formed in the sleeve E, and upon engaging the shoulder e', of the recessed portions, the sleeves are interlocked and complete their outward stroke as a single unit. It will be seen upon reference to the diagrammatic views that in the first half of the suction stroke (see Fig. 2) the sleeve F, moves outwardly leaving the sleeve E, at the end of the cylinder until the expanding ring J, engages the shoulder e', of the tapering recess formed in the sleeve E.

The sleeves E and F, then complete their stroke in fixed relation to each other (see Fig. 3) drawing into the cylinder a relatively small charge of fuel. The fuel charge is then compressed,—the sleeve F, telescoping within the outer sleeve E, (see Fig. 4)—the air between the ends of the respective sleeves passing out between the spaced ends of the expanding ring J. The sleeves then move together compressing the charge ready for firing, as indicated in Fig. 1, of the drawing;—the explosion then takes place driving both sleeves of the piston to the end of the cylinder, (see Fig. 5) thereby securing the efficiency of a long stroke motor with the admission of only a relatively small fuel charge. Fig. 1 also shows the position of the sleeves of the piston at the end of the exhaust stroke which follows. The cycle of operations just described is then repeated.

Having thus described my invention, what I claim is:

1. In an internal combustion engine, a piston comprising telescoping sleeves, having a limited independent movement for a portion of each stroke of the piston and a unitary movement for the remainder of the stroke, one of the sleeves having an inclined recess, and a laterally yieldable member carried by the other sleeve to coöperate with the inclined recess.

2. In an internal combustion engine, a piston comprising telescoping sleeves having a limited independent movement for a portion of each stroke of the piston and a unitary movement for the remainder of the stroke, one of the sleeves having a tapering wall and a shoulder at the base of the tapering wall and an expanding ring mounted upon the other sleeve and adapted to coöperate with the tapering wall.

erate with the said tapering wall and shoulder.

3. In an internal combustion engine, a piston comprising two telescoping sleeves, a piston rod connecting the inner sleeve with the crank shaft of the engine, and an expanding ring fitted to the inner sleeve adapted to enter an inclined recess in the outer sleeve, whereby the sleeves while free to move independently of each other for a

portion of the piston stroke are adapted to interlock that they may operate as a unit for the remainder of the piston stroke.

In testimony whereof, I sign this specification in the presence of two witnesses:

JOHN S. BARNES.

Witnesses:

S. E. THOMAS,
N. H. HOUSE.
